(57)

CLAIM

I claim the ornamental design for a grip, as shown and described.

DESCRIPTION

FIG. 1 is a perspective view of a grip, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed lines are included to depict portions of the grip that form no part of the claimed design.

1 Claim, 4 Drawing Sheets
